UNITED STATES PATENT OFFICE.

BERT D. GILSON, OF CHICAGO, ILLINOIS.

ENGINE STARTER.

Application filed September 21, 1921. Serial No. 502,146.

To all whom it may concern:

Be it known that I, BERT D. GILSON, a citizen of the United States, residing at Chicago, in the county of Cook and State 5 of Illinois, have invented new and useful Improvements in Engine Starters, of which the following is a specification.

This invention has relation to engines, and it has particular reference to starting 10 means for such engines.

Some engines are not entirely self starting, and the engines of another class will usually not start at all until some outside source of power is applied for starting purposes. A steam engine, or at least a one cylinder engine, often comes to a stop on the dead center and some external power must be applied to start it over the dead center. Internal combustion engines in most cases 20 will not start without cranking or the application of some such equivalent application of outside power.

The object of the present invention is the provision of improved means for starting 25 such engines, and structures illustrative of my invention are hereinafter fully described and illustrated in the appended drawing, of which:

Fig. 1 is a side elevation of an engine embodying the invention,

Fig. 2 shows, on a very much larger scale the starting mechanism of my invention in its relation to co-operating parts of the engine,

Fig. 3 is a similar view, in which a modification is embodied, and

Fig. 4 is a fragmental view showing parts of the structure of Fig. 1.

The engine of Fig. 1 is of the internal 40 combustion type, having on its crank shaft 1 a fly wheel 2, and on the periphery of this wheel is provided a toothed portion 3, which may be detachable or part of the wheel, as desired. Suitably located on the 45 engine casting, or the crank case, is an electric motor 4, from which extends a shaft 5 parallel with the engine crank shaft. On the motor shaft 5 is mounted a toothed pinion 6, through the medium of which rotations of the said motor are communicated 50 to the fly wheel for the purpose of starting the engine.

Referring now to Fig. 2 it is seen that the motor shaft 5 supports rigid collars 7 and 8, in spaced relation, and that a sleeve 9 is mounted on the shaft between the said

collars. Concentric with the shaft and sleeve is a cylindrical housing 10, which may be suitably secured to the sleeve, as by a plurality of pins or screws 12, or it may be made a part of the sleeve. In any case, for the purpose of this description it does form part of the sleeve, and it is provided with internal screw threads 10^a. The aforesigned pinion 6 is slidably fitted on the sleeve, and it is provided with screw threads 6^a, meshing with the screw threads of the housing.

The instrumentalities so far described 70 coact to start the engine in the following manner. The motor, motor shaft, sleeve and housing all start together when the circuit through the motor is closed, and they gain speed instantly. But the pinion 6 is free to rotate on the sleeve, and it is by its inertia opposed to a change of condition. It does not start at once, and it gains speed 75 more slowly. Yet it cannot remain stationary because of the intermeshing screw threads 6^a, 10^a, and as a consequence it is forced to advance axially on the sleeve.

The face 6^b of the pinion is positioned 80 very close to the edge of the fly wheel gear 3, into engagement with which it now advances, and as soon as it touches this gear 85 it is held against rotation. It must now continue to advance until its face 6^b strikes the shoulder portion 7^a of the collar 7, whereupon it becomes locked for positive rotation by and with the motor shaft, and 90 as a consequence commences to turn the fly wheel to start the engine. The moment the engine is started it is found that the fly wheel commences to increase the speed of the pinion, with the result that the latter rotates 95 faster than the motor shaft and commences to return into the housing, finally again to become disengaged from the fly wheel gear. If the motor stops before the return of the pinion, the result will only be to increase the 100 speed of return of the pinion.

An electric motor is a very flexible apparatus, and it will stand much abuse. Yet it is well to introduce some sort of cushioning means to absorb the shock when the pinion strikes the collar 7 and meets the sudden resistance of the fly wheel with its engine connections. Such means may take the shape of a suitable buffer element 25, see Fig. 3, which is capable of some compression. Or it may be accomplished by 110 the interposition of yielding driving con-

nections, as shown in Fig. 2. Within the sleeve 9 is an annular space, in which a resilient member 13 is seated, and the latter is made with projecting ends 13^a, 13^b, which in turn lodge in a notch 7^b of the collar 7 and 9^c of the sleeve 9, as best indicated in Fig. 4. Having introduced this resilient member it is seen that rotations of the motor shaft are transmitted through said member to the sleeve, which otherwise is free to rotate on the shaft, and that the desired cushioning effect is obtained. It is important to note that no screws or other fastening means are employed in connection with the resilient member 13, which is held firmly in position in the notches referred to, and which is of great strength, having no loops or eyes capable of breaking.

The housing 26, of the structure of Fig. 3, is rigid on the motor shaft 27, and the pinion 28 may ride directly on this shaft, otherwise the structure may be exactly like the device of Figs. 1 and 2. The resilient member 25 may well take some other form, so long as it performs the function of absorbing the shock.

Other starters are made utilizing the old principle of advancing a pinion into mesh with the engine fly wheel upon starting the motor, as described, but in such starters the mistake has been made of mounting the pinion on a screw, in which case the perforation through the pinion is provided with corresponding screw threads. The closer to the axis of the shaft the screw threads, by which the pinion is advanced, are placed, the greater is also the frictional resistance between the screw and pinion. For this reason it will be observed that additional means, such as counterweights, have been added to the pinion of such devices in order to delay the rotation of the pinion and thereby to attain the required advance movement.

In the structures of my invention the screw threads have been brought far enough away from the axis of the motor shaft to reduce the frictional resistance sufficiently to be safely overbalanced by the inertia of the pinion. Due to this construction it is found that no counterweight or other retarding means is required in the structure of my invention.

A yielding driving connection between the drive shaft and the sleeve is old in the art, and the novelty of my structure resides in enclosing this yielding member within the sleeve. Another novelty of my structure is the feature of enclosing the pinion when it is not projected into engagement with the fly wheel incident to starting the

engine. The whole device is very simple; its cylindrical outline gives it a pleasing compact and trim appearance, and it is noticed that no part projects, but that it is perfectly smooth and incapable of catching the operator's dress.

In some small automobiles very little room is provided, into which to mount a starting mechanism, and for such small machines my device is particularly adapted. In larger automobiles much more room is found, and the requirements less exacting. I have shown the screw threads 6^a cut directly into the outer periphery of the pinion 6, but I can, of course, in larger machines, or wherever there is sufficient room cut these threads on a separate piece and attach this piece to the pinion. Such are mechanical modifications, but the principle remains, namely, that the screw threads must rise from the periphery of the pinion in order to be far enough removed to reduce the axial friction, as hereinbefore explained.

I claim:

1. The combination with an engine and a starting motor, of a pinion on the motor shaft provided with screw threads rising from the outer periphery of the pinion teeth, and a housing covering the pinion and having internal screw threads in mesh with the pinion threads, whereby the pinion is caused to advance along the shaft upon starting the motor and housing.

2. The combination with an engine and a starting motor, of a sleeve on the motor shaft, a pinion movable on said shaft and provided with screw threads rising from the outer periphery of said pinion, a cylindrical housing rigid with said sleeve and having internal screw threads meshing with the pinion threads for the purpose of advancing the pinion into engagement with a gear wheel of the engine, and a buffer device capable of absorbing the shock incident to such engagement.

3. The combination with an engine and a motor for starting said engine, of a sleeve on the motor shaft, a pinion on said sleeve and slideable into engagement with a gear wheel of the engine, said sleeve made with a cylindrical flange normally covering said pinion and provided with internal screw threads in mesh with screw threads rising from the outer periphery of said pinion, and a resilient member within said sleeve for absorbing the shock incident to such engagement.

In testimony whereof I have hereunto affixed my signature.

BERT D. GILSON.
